UNITED STATES PATENT OFFICE.

JAMES L. MCQUARRIE, OF CHICAGO, ILLINOIS, ASSIGNOR TO THE WESTERN ELECTRIC COMPANY, OF CHICAGO, ILLINOIS, A CORPORATION OF ILLINOIS.

TELEPHONE-EXCHANGE SYSTEM.

SPECIFICATION forming part of Letters Patent No. 772,900, dated October 18, 1904.

Application filed January 14, 1901. Serial No. 43,279. (No model.)

To all whom it may concern:

Be it known that I, JAMES L. MCQUARRIE, a citizen of the United States, residing at Chicago, in the county of Cook and State of Illinois, have invented a certain new and useful Improvement in Telephone-Exchange Systems, of which the following is a full, clear, concise, and exact description.

My invention relates to a telephone-exchange system, and more particularly to a system wherein a private branch telephone-exchange is provided instead of a single instrument at a substation of a large exchange.

In large cities it is not uncommon that a business-house requiring considerable telephone service to other parts of the city and also requiring a local telephone system for communicating between its departments will have a large number of telephone instruments distributed at various points throughout the premises, and all of said instruments will be connected with a private branch exchange-switchboard. One or more trunk-lines corresponding to ordinary subscriber's lines will then be provided between the private branch exchange and the main central office. With such a system when a subscriber of the large exchange desires communication with a particular department of the business-house having the private exchange he will call up the central office in the usual way and ask for connection with the private exchange. The central-office operator will then make connection with the trunk-line leading to the private exchange and apply calling-current. The private-exchange operator upon perceiving the signal thus transmitted will insert her answering-plug in the spring-jack of the trunk-line, at the same time connecting her telephone in circuit. She will then inquire of the calling subscriber the name of the person or department wanted and having obtained this information will complete the desired connection. When a person at one of the instruments of a private exchange desires a connection with a subscriber of the large exchange, he will transmit his order to the private-exchange oper-

ator, who will connect his instrument with the trunk-line leading to the central office, whereupon the central-office operator will answer the call in the same manner as though it came from an ordinary substation. The connection of one of the private-exchange instruments with the main central office will not, of course, interfere with local communication between any other two instruments of the private exchange.

In telephone systems of the character described it is desirable that all the substations of the private exchange should have substantially the same equipment; but it is also desirable that through connection to the large city exchange should be permitted only to a certain few designated instruments. The object of this of course is to limit the use of the trunk-lines strictly to business purposes, and so to reduce the number of trunk-lines required. Where the common battery system is used, while a local source of current is provided at the private-exchange office for local connections it is desirable that for through connections to the city exchange the substation-transmitters should be operated by current derived from the main-exchange battery—that is, the battery bridged across the central-office-operator's plug-circuit—the same as though connection were had from the central office to an ordinary individual line.

The object of this invention is to provide a telephone system in which these results are attained.

In accordance with my invention an electromagnetic switch is connected with the private-exchange-operator's plug-circuit, which is brought into operation by plugging into certain of the lines but not into others to disconnect or apply the local source of current for talking. Blocking mechanism is also provided for preventing telephonic communication, as by positively rendering the trunk-line or other telephonic circuit inoperative when connection is made between the trunk-line and a substation which is not designed to be connected therewith.

My invention further contemplates im-

proved means at the private-exchange office for controlling signals at the central office of the large exchange.

My invention is illustrated in the accompanying drawing, which is a diagram showing a trunk-line extending from a central office to a private-exchange office and also showing two subscribers' lines of the private exchange, together with the apparatus involved in connecting and disconnecting lines, the system being constructed and equipped in accordance with my invention.

The trunk-line, which extends in two limbs or line conductors 1 2 from the central office 15 A to the private-exchange office B, is provided at the central office with the usual line-signal apparatus for indicating a call. Such signal apparatus is similar to that used on all subscribers' lines of common-battery exchanges and does not require detailed description. At the private-branch-exchange office B the limbs 1 2 of the trunk-line terminate in line-springs a' a^2 of a spring-jack a . A line-indicator or drop b is connected in a 25 terminal loop of the trunk-line by way of two contacts, against which the line-springs a' a^2 normally rest when no plug is inserted in the jack. Condenser b' is included in the terminal loop containing the drop b , so that the 30 circuit of the central-office line-signal battery will not be closed through said terminal loop. The continuity of the two conductors 1 2 is controlled by a blocking-relay c . Said relay normally maintains the continuity of the 35 trunk-line, but is adapted when excited to sever both limbs thereof. The magnet-winding of the relay c is included in a conductor 3, which extends from the test-ring or third contact-piece a^3 of the spring-jack a to the 40 pole d' of the local-exchange battery d .

At the central office the trunk-line is connected with the usual terminal spring-jack e and is equipped in the same manner as an ordinary subscriber's line. I have illustrated 45 an operator's plug-circuit at the central office, adapted to make connection between the spring-jack of the trunk-line and the spring-jacks of other lines of the exchange. This plug-circuit is of the ordinary type and need 50 not be particularly described. It is equipped with the usual supervisory relays f' f'' included in the sleeve-strand thereof, and a battery f^2 is connected in a bridge of the plug-circuit between the windings of a repeating- 55 coil. The relays f' f'' control subsidiary signals f^3 f^4 , and when one of the plugs of the plug-circuit is inserted in the spring-jack e of the trunk-line the supervisory relay corresponding 60 to such plug is thus responsive to the flow of current from battery f^2 through the trunk-line. A calling-key f^5 is associated with one of the plugs, said calling-key being adapted when depressed to sever the cord-circuit and connect the terminal contact-pieces of the calling-plug with the poles of an alternating gen- 65

erator. When alternating calling-current is applied to the trunk-line to signal the private-exchange office, such current will traverse the terminal loop, which includes the condenser b' and trunk-line drop b , whereby said drop 70 will be caused to display its signal.

Two substation instruments G H of the private exchange are illustrated, said substation instruments being connected with corresponding spring-jacks g h at the private-exchange 75 office. Thus the line-springs g' g^2 of spring-jack g are connected with the line conductors leading to substation G, and line-springs h' h^2 of spring-jack h are similarly connected with the line conductors leading to substation H. Line indicators or annunciators are provided for the substation telephone-lines, each line having an annunciator connected in a bridge thereof, together with a source of current at the private-exchange office, and the spring-jack of each line is adapted when plugged into to open the circuit of this bridge in a well-known manner. It is designed that station G shall be used not only to communicate with other stations of the private exchange, 80 but also to be given through connection over the trunk-line with the city exchange, while substation H, on the other hand, is intended to be allowed only local service in the private exchange. The equipment of the two stations 85 G and H and of their line apparatus at the central office is identical, with the single exception that the spring-jack of the line of station H is provided with a ring contact h^3 , which is connected by a conductor 4 with the pole d^2 of battery d . The spring-jack g has a similar ring contact; but no battery connection therefor is provided.

The private-exchange operator is provided with a number of pairs of plugs and their link conductors for making connections. One of these pairs of plugs with a cord-circuit therefor is illustrated in the drawings. Each of the plugs i k is provided with three contact-terminals—the usual tip, ring, and sleeve contacts—adapted to register with corresponding contact portions of the spring-jacks. Thus, for example, when plug i is inserted in spring-jack a the parts i' i^2 i^3 register with and make contact with the parts a' a^2 a^3 of said spring-jack. The tips i^2 k^2 of the plugs i k , respectively, are united by the conductor 5 of the cord-circuit, and similarly the ring contacts i' k' are united by conductor 6, and contacts i^3 k^3 are united by conductor 7. The 110 listening-key l is adapted when depressed to connect the private-exchange-operator's telephone set in a bridge between the cord-strands 5 6. The ringing-key m is adapted when depressed to sever the conductors 5 6 and connect the ends of said conductors which lead to the calling-plug k with the poles of a calling-generator.

The local-exchange battery d is connected in a bridge between the conductors 5 6 of the 115 120 125 130

plug-circuit, said bridge being controlled by a relay n . The windings o' o^2 of a retardation-coil o are included in the bridge, one on either side of the battery d . The relay n is of comparatively high resistance and has two armatures, one of which is connected with the conductor 5 through the winding o' , and the other is connected with conductor 6 through the winding o^2 . The armatures normally rest 10 on back contacts, which are connected with the poles d' d^2 , respectively, of the battery d . When said armatures are attracted, they close against a pair of front contacts united by a conductor which includes a retardation-coil 15 p . Normally, then, the battery d is included in a bridge of the cord-circuit between the windings o' o^2 of the retardation-coil o , and when the relay n is excited the battery is cut off and the retardation-coil p substituted 20 therefor in the bridge-circuit.

An electromagnetic supervisory indicator is included in the circuit of the cord-strand 6 and is responsive to current flowing therein. Said indicator is adapted to display its signal 25 when inert.

The magnet-winding of relay n is included in a conductor 8, which connects the pole d^2 of the battery d with the conductor 7 of the cord-circuit. In order that said relay n may 30 be excited, therefore, it is necessary that the conductor 7 be electrically connected with the other pole, d' , of the battery. This is accomplished when either of the plugs i k is inserted in the spring-jack a of the trunk-line, since 35 the contact a^3 of said spring-jack is connected to the pole d' of the battery d by the conductor 3. No circuit through the relay n is completed when both the plugs are inserted in local jacks, since the ring contacts h^3 of 40 lines designed for private service only are connected with the same pole, d^2 , of the battery, and the ring contacts of jacks g of lines permitted exchange service also have no connection at all.

45 The relay c , which is adapted when excited to sever the circuit of the trunk-line, constitutes a blocking device to prevent the use of the trunk-line from substations similar to substation H. While circuit is always completed through said relay c whenever connection is made with the trunk-line, yet when the trunk-line is connected with a substation of type G the circuit through said relay includes the windings of the high-resistance 50 relay n , so that sufficient current does not flow in the circuit to excite relay c ; but when one of the plugs is inserted in the trunk-line jack and the other is inserted in the jack of a station of class H a low-resistance circuit will 55 be completed through the relay c from the pole d' of the battery d to the ring a^3 of jack a , contact i^3 of plug i , conductor 7 of the plug-circuit to contact h^3 of plug h , thence to the ring contact h^3 of the spring-jack h , and 60 so by way of conductor 4 to the other pole, 65

d^2 , of the battery. Current flowing in this circuit will excite the relay c sufficiently to cause the same to draw up its armatures, whereby the circuit of the trunk-line will be broken and telephonic communication prevented. 70

Whenever connection is made between the trunk-line and a station of class G, the relay n is excited by current flowing in the local circuit 378, whereby said relay draws up its 75 armatures and cuts off the battery d from its bridge connection with the main conductors 56 of the plug-circuit, at the same time substituting the retardation-coil p therefor. The substation-transmitter is then supplied with 80 current, not from the battery d , but from the main battery at the central office of the city-exchange, the same as though the substation were an ordinary substation of that exchange. The maintenance of the bridge-circuit, including 85 retardation-coils o and p , during the connection with the trunk-line serves to maintain a circuit for the supervisory relay f of the central-office-operator's plug-circuit independent of the condition of the telephone-switch 90 at the private-exchange substation. The central-office-operator's supervisory lamp, therefore, is not lighted to indicate a disconnection-signal until the connecting-plug at the private exchange has been removed from the 95 trunk-jack. If it were desired that the operator at the central office of the main exchange should have the supervision of the connection, the retardation-coil might be omitted, so that no bridge of the private-exchange-operator's 100 plug-circuit would be established when the relay n cuts out the battery.

To recapitulate, the telephone-lines of the private branch exchange are divided into two classes—those which are permitted both private and also through exchange service and those which are permitted only private local service. A blocking device c is provided for preventing telephonic communication between the city exchange and substations of 110 the private exchange which are not designed for through connection, and said blocking device is actuated whenever connection is made between the trunk-line and such a substation. It is obvious that various means may be provided for blocking communication other than by severing the trunk-line, and I do not wish to be limited to the precise means illustrated. 115

When connections are made between local substations of the private branch exchange, current for exciting the substation-transmitters is derived from the local battery d ; but when through connection is made from a substation to the central office A the local battery d is cut off and current is derived directly from 120 the main central-office battery. When battery d is cut off, a retardation-coil p is substituted therefor, and the bridge is completely 125 independent of said battery. The supervisory-signal device of the A operator's plug-circuit 130

thus receives current as long as connection is maintained with the trunk-line at the B switchboard and is independent of the private-exchange-substation apparatus.

5 Having thus described my invention, I claim as new, and desire to secure by Letters Patent, the following:

1. In a telephone-exchange system, the combination with telephone-lines of different classes extending from substations to terminal spring-jacks at an exchange-switchboard, of a pair of connecting-plugs and link conductors uniting them, for connecting lines together by plugging into the spring-jacks thereof, a trunk-line also having a terminal spring-jack at the exchange-switchboard, adapted to be plugged into by a plug of the pair aforesaid, a blocking device for preventing telephonic communication between a substation and the station of the trunk-line, and means, controlled by connection of the trunk-line with any one of the lines of a certain class, for actuating said blocking device, substantially as described.

25 2. In a telephone-exchange, the combination with a number of telephone-lines of different classes extending from substations to an exchange-switchboard, of a telephone trunk-line extending from said exchange-switchboard to a distant exchange, means for connecting any two of said telephone-lines together and for connecting either of said lines with the trunk-line, and blocking mechanism, made operative in connecting said trunk-line with any one of the lines of a certain class, said blocking mechanism being adapted to render inoperative the telephonic circuit thereby established.

35 3. The combination with local telephone-lines and a trunk-line, each having switch-terminals at an exchange, said trunk-line having a source of current in a bridge thereof at the distant station, of link conductors for uniting any two lines at the said switch-terminals, a local source of current in a bridge of said link conductors for supplying current to the telephones of local lines united thereby, an electromagnetic switch adapted when actuated to disconnect said local source of current, and 45 a local circuit for said electromagnetic switch closed in connecting said link conductors to the trunk-line, whereby current for the local line is supplied from the distant trunk-line battery during the connection of said local line with the trunk-line.

4. The combination with a number of local telephone-lines having circuit-controlling switches at the substations thereof and switch-terminals at an exchange office, of link conductors for uniting the lines, a local source of current in a bridge of the link-conductors for supplying current to local lines united thereby, a special line also having a switch-terminal at said exchange office, a battery and a signal device in the circuit of said special line

at the distant station thereof, and a switch at the aforesaid exchange office adapted to disconnect the local source of current from the link conductors and complete an independent bridge-circuit of low resistance across said link conductors, whereby when a local line is united to said special line current is derived from the battery in the special line, and the circuit through the signal device of said special line is maintained independent of the switch at the substation of the connected local line.

5. The combination with telephone-lines of different classes having terminal switches at an exchange office, and link conductors for uniting lines at the switch-terminals thereof, a local battery and circuits connecting the same in a bridge of the link conductors, an electromagnetic switch controlling the connection of said local battery in said bridge, a portion of a local circuit controlling said electromagnetic switch associated with the link conductors, and conductors associated with the terminal switches of a particular class of lines adapted to complete the local circuit controlling said electromagnetic switch when connection is made with such lines, whereby the local battery is applied to the link conductors or not, according to the type of line with which connection is made.

6. The combination with a telephone trunk-line extending between two switchboards A B, of a source of current in a bridge of the line at the switchboard A, and a supervisory device connected in the circuit, a spring-jack terminal for the line at the other switchboard B, a pair of plugs and a plug-circuit at the B switchboard for connecting lines together, a source of current *d* and a retardation-coil normally connected in a bridge of the plug-circuit, and an electromagnetic switch actuated by connection of the plug-circuit with the trunk-line, adapted to disconnect the source of current *d* from the bridge of the plug-circuit and to complete said bridge independent of said source of current, substantially as described.

7. The combination with a telephone trunk-line extending between two switchboards A B, of other telephone-lines having spring-jack terminals at switchboard B, such other lines being divided into two classes, a plug-circuit connected with the trunk-line and having a plug-terminal adapted for insertion in the spring-jacks of the other lines to make connection therewith, an electromagnetic blocking device, a circuit including a source of current, for said electromagnetic blocking device, and switch-contacts associated with the spring-jacks of all the lines of a particular class for establishing the circuit of said blocking device when the plug is inserted in any spring-jack of said class, substantially as described.

8. In a telephone-exchange, the combination

with a number of telephone-lines of different classes centering in an exchange-switchboard, of spring-jacks for the lines and a pair of plugs and a plug-circuit for uniting the lines, 5 a special line 1 2 also having a spring-jack in the exchange-switchboard, an electromagnetic switch adapted to interrupt the telephonic circuit of said special line, and a circuit for said electromagnetic switch automatically established in connecting the special line with any 10 of the lines of a particular class, whereby communication between the special line and the lines of such particular class is prevented, substantially as set forth.

15 9. The combination with telephone-lines having terminal switches at an exchange office, of link conductors for uniting the lines,

a special line having a battery and a signal operated thereby in its circuit at the distant station, a source of current at the exchange 20 office, a switch adapted to connect said source of current in a bridge of the link conductors, and a high-impedance bridge of said link conductors independent of said source of current adapted to be completed by said switch in its 25 alternative position whereby the signal of said special line is controlled.

In witness whereof I hereunto subscribe my name this 28th day of July, A. D. 1900.

JAMES L. McQUARRIE.
